CLAIM

The ornamental design for a football wreath, as shown and described.

DESCRIPTION

FIG. 1 is a perspective view of a football wreath showing my new design;

FIG. 2 is a front elevation view thereof;

FIG. 3 is a rear elevation view thereof with the eyelet and stem details shown as broken lines for illustrating that the eyelet and stem details form no part of the invention;

FIG. 4 is a right side view thereof;

FIG. 5 is a left side view thereof;

FIG. 6 is a bottom plan view thereof; and,

FIG. 7 is a top plan view thereof.
